UNITED STATES PATENT OFFICE.

ARTHUR R. BOAL AND CHARLES O'BRIEN, OF NEW YORK, N. Y.

PRESS.

Application filed February 24, 1920, Serial No. 360,917. Renewed April 7, 1926.

This invention relates to presses, and particularly to a press for compacting and molding relatively soft material.

The object of our invention is to provide

- 5 a press adapted to compact and mold a charge of soft material, which may be in lump form, eject the molded charge and reset itself automatically in readiness for a succeeding charge.
- 10 A further object is to provide press feeding means in which a plurality of separate lumps of soft material may be placed, and which is adapted to feed the lumps one by one to the press at the proper time.

15 The manipulation of soft material, particularly when of an adherent or sticky nature, involves peculiar requirements which render an ordinary press unsuitable for use therewith. Such material tends to ooze through 20 the cracks and over the edges of the parts, and to gather on moving surfaces, rapidly clogging the machine. The process of compression also tends to cause the material to adhere to the walls of the mold, rendering 25 rapid and clean ejection of the charge therefrom very difficult.

When handling sticky materials, it is common to employ a surfacing substance, usually in the form of powder, to prevent adhesion. 30 This is particularly used in connection with edible materials, certain kinds of which are usually surfaced with a fine powder. Materials treated in this way require careful manipulation, especially in machines, as any 35 pressure sufficient to break through the light surface coating is certain to cause the material to adhere to the penetrating element. Furthermore, friction tends to rub off the surface and expose the sticky material. Consequently, sliding conveyors or ejecting 40 means are highly objectionable with this class of material.

We have devised a press adapted to avoid these difficulties, and which is both simple 45 and strong in construction, and rapid in operation.

We have also provided a novel type of 50 mold, so constructed that the molded charge is ejected without the use of a plunger or similar element. The ejecting mechanism is consequently peculiarly adapted to handle charges of sticky material, as such charges

tend to adhere to an ejecting plunger after clearing the mold. Furthermore, the elimination of the plunger substantially simplifies the construction of the machine. 55

A further object of our construction is the provision of a mold composed of a plurality of parts, adapted to be held firmly in closed position during the compressing of the material, and opened thereafter in such a way that adherence of the charge to the major portion of the mold walls is necessarily broken, the movement of said walls tending to eject the charge automatically. 60 65

We have also constructed all the parts of the mold so that material oozing through cracks therein will lodge in cavities in the parts, the subsequent movements of which tend to dislodge said material, especially 70 after repeated operations have caused it to accumulate.

Our press is also constructed to accommodate charges varying in size, and to exert the same pressure thereon, regardless of the size 75 thereof.

Another object of our invention is to arrange the parts of the press so that they are readily accessible for cleaning, the portions in which material may accumulate being 80 readily accessible, thus minimizing any delay caused by stoppage of the press. The main operating parts are also readily and rapidly removable and replaceable.

We have also provided improved means 85 for feeding a succession of charges to the machine. While various means may be used for this purpose, the one shown is adapted to feed a succession of lumps of material, generally similar in size. In feeding charges 90 of this nature, it is essential that they should not be subjected to substantial pressure, as such a condition would cause them to adhere to each other and to the mechanism. It is likewise necessary to present them in rapid 95 succession to the press in order to permit high capacity of production. We have provided a feeding means which combines speed of delivery with the absence of substantial pressure on the lumps or charges; and preferably one that is automatically operated by the press to deliver the successive charges 100 at the right moment.

While our invention includes improve-

ments in the press and in the feeding mechanism, it will be apparent that other methods may be used for feeding the press, although the specific form shown is particularly 5 adapted therefor and cooperates therewith in a novel manner.

One difficulty with presses working on soft material is the deformation of the formed charges by air trapped in the mold 10 during the pressing operation, owing to the tight fitting of the parts. An object of our invention is to avoid this difficulty by providing means for permitting the escape of trapped air during pressing to insure rapid 15 and perfect molding. We also prevent charge distortion due to suction during the retraction of the pressing plunger from the mold, by providing means for permitting ingress of air beneath the plunger.

20 Furthermore, while a single press and feeding means therefor have been disclosed, it will be apparent that our invention is equally applicable to a gang press having a plurality of similar press units which may 25 be separately operated or actuated in common by mechanism similar to that disclosed, and which may be fed simultaneously in any desired way.

30 Further objects and advantages of our invention will be apparent from the following description, taken in connection with the accompanying drawings, in which:

Fig. 1 is a side elevation,

35 Fig. 2 is a detail vertical sectional view through the press, showing the parts in pressing position,

Fig. 3 is a view similar to Fig. 2, showing the parts in ejecting position,

40 Fig. 4 is a plan view, parts being broken away,

Fig. 5 is a fragmentary top plan view of the mold,

45 Fig. 6 is a fragmentary front view of the press in closed position, parts being broken away,

Fig. 7 is a detail of one form of gate employed in the feeding means, and

50 Fig. 8 is a top plan view of a portion of the feeding means, showing an alternative form of gate.

55 The mold is carried by a slide block 10 mounted to reciprocate on base 11, as by forming a pair of parallel guide walls 12, the inner faces of which include ways for the block 10. Means is provided for retaining the block in proper engagement with the ways, a pair of retaining plates or gibs 13 being disclosed, mounted on the top of guide walls 12.

60 The mold employed is of the sectional type, including a plurality of wall elements which are positively held in closed position to form a vertical sided mold with a closed bottom in which the material is placed, a compressing element entering the top of the

mold and compacting the material. The mold is then thrown open by separating the wall segments, this operation preferably being performed so rapidly that the charge is forcibly ejected. The wall segments then 70 close, and the operation is repeated.

75 It will be apparent that various means for opening and closing the mold sections may be employed. In the preferred form the mold includes a back wall 14 and side walls 15 hinged to the back wall as at 16, the inner faces of the side and back walls forming the sides of the mold, which is disclosed as cylindrical in form though, obviously, other contours may be employed. The back wall 14 is connected to slide block 10 and, if desired, may constitute the forward part thereof.

80 Means is provided for retaining the side walls 15 in closed position during the compressing operation, and then throwing them sharply outward, preferably projecting the back wall forward at the same time, so as to forcibly eject the charge. The retraction of the back wall 14 and the simultaneous 85 closing of the side walls return the mold to closed position, shown in Fig. 2.

90 It will be apparent that the mold may be operated upon a fixed base, the forward 95 ejecting movement tending to throw the charge forward off of the base; but it is preferable to use a bottom plate 17 hinged to the back wall 14, as at 18, and adapted to drop away from the side walls of the mold during the ejecting movement to break the 100 connection between the charge and the bottom plate. Plate 17 preferably carries a central raised portion or table 19, the edges of which coincide accurately with the lower 105 edges of the mold, for a purpose to be hereinafter indicated.

110 Means is provided for simultaneously swinging side walls 15 outwardly and dropping bottom plate 17 downwardly to effect the ejection of the charge. Various forms 115 of mechanism may be provided for this purpose, the one disclosed being operated by the forward movement of the mold from the position shown in Fig. 2 to that shown in Fig. 3. When the opening of the mold is 120 produced by such a forward shift, the side walls 15 are preferably spread by means carried by said walls and engaging fixed portions on the frame of the machine, adapted to throw the walls outward when the mold is shifted forward, and to throw them inward into closed position upon the retraction of the mold. Various forms of mechanism may be provided for this purpose, the one disclosed including links 20, pivoted at 125 21 to the side walls adjacent their forward ends, the opposite end of each link being provided with a slot 22, through which a pivot stud 23 passes, the latter being mounted on the frame of the machine and prefer- 130

ably removable to facilitate the removal of the sliding mold. If desired, links 20 may constitute the sole means for opening and closing the sides of the mold; but in the preferred form it is desirable to maintain the side walls 15 in engagement with guide walls 12 until the mold has completed part of its forward ejecting movement, reaching a point at which the walls are cut away to permit the links 20 to operate, this type of construction serving to open the mold with a jerk and facilitating the ejecting of the charge. With this type of construction it is necessary to have slot 22 elongated in form, to permit forward movement of the mold for part of its travel before the links start their opening action.

Means is provided for dropping the bottom plate 17 away from the mold body. When the mold is opened by the forward shifting movement, this means may include a support for the bottom plate 17, adapted to retain it against the bottom of the mold when in closed position, as in Fig. 2, the support being cut away adjacent the forward end of the plate when in such position, so that the forward shift of the mold will permit the bottom plate to swing downwardly over the edge of the support. In the specific form disclosed, plate 17 is provided with a downwardly projecting lip 24 adjacent its forward end, bearing against an inclined supporting surface 25 on the base of the machine, the forward shift of the mold carrying lip 24 down surface 25, and swinging bottom plate 17 downwardly, thus tending to break any adhesion between table 19 and the charge, which would be compelled to suffer considerable distortion to follow the bottom plate 17. The axis of pivot 18 is preferably above the center of gravity of bottom plate 17, so that the sharp forward movement of the mold will tend to throw said bottom plate away from the mold.

While this is the preferred form of support for the plate, it is obvious that many other variations therein are possible, such as means carried by the base directly beneath the intermediate portion of bottom plate 17.

It will, of course, be understood that means for separating side walls 15 and dropping bottom plate 17 are preferably so arranged that they either operate simultaneously, or if desired, depress bottom plate 17 slightly prior to the opening of side walls 15.

It will be apparent that a compressed charge tending to adhere to the walls and bottom of the mold must necessarily be separated from the major portion of the mold surface by the mold opening process above outlined, the sharp forward movement of the mold and the relatively small area to which the charge may remain attached after the mold is opened combining to eject the charge in a particularly effective manner.

Furthermore, we have provided a construction by which the charge is ejected without sliding along any surface whatever, another feature which is particularly suitable where the charge tends to adhere to the mold, as such substances always tend to adhere to surfaces over which they slide.

We have also constructed the parts of the mold so that material oozing through the mold joints will not interfere with the successive opening and closing of the mold. To accomplish this result, we have provided cut-away portions 26 at the rear of each of the joints between side walls 15 and back wall 14, and similar cut-away portions 27 in the meeting edges of the side walls 15.

Table 19 is, furthermore, so constructed that any material forcing its way between said table and the lower edges of the mold walls will rest on the adjacent parts of bottom plate 17, where it may collect without interfering with the operation of the machine, grooves 28 being provided, if desired, in the lower faces of the mold walls adjacent the edges of table 19, to permit accumulation of a substantial quantity of material without affecting the operation of the machine.

It will likewise be apparent that the sharp outward throw of side walls 15 and the sudden drop of bottom plate 17 when the mold is opened will tend to throw out any substantial accumulations of material in the cut-away portions, the machine thus tending to automatically clean itself, reducing the possibility of clogging to a minimum.

The walls of the mold are substantially vertical, and a plunger 29 is provided, which is adapted to enter the top of the mold after a charge has been placed therein, and compress and mold the charge, the plunger preferably rising prior to the opening of the mold. A standard 30, mounted on the base 11, carries a bearing 31 for plunger 29, the bearing preferably being in two parts hinged to each other, as at 32, and detachably connected, as by thumb screw 33, permitting ready access to the plunger and bearing for cleaning or replacement.

Plunger 29 is preferably constructed to exert substantially the same pressure on a charge, regardless of its size. One means for accomplishing this purpose is disclosed, consisting of a plunger head 34 slidably mounted in the lower end of plunger 29 and retained therein by a transverse pin 35, as shown best in Fig. 6, the ends of the pin working in vertical slots 36 in the walls of plunger 29, spring 37 tending to force the plunger head 34 downwardly under a relatively fixed pressure, permitting it to adjust itself to charges of various sizes. The lower end of plunger head 34 is adapted to fit snugly within the walls of the mold, and preferably is cut away adjacent its lower

edge, as at 38, to provide a space in which portions of the material may gather without obstructing the operation of the press.

It will be apparent that the reciprocation of plunger 29 will tend to dislodge all such material, particularly after a considerable quantity has accumulated, without interfering with the continued operation of the machine.

10 When charges of soft material are used, the necessity for a relatively close fit between the parts of the mold tends to cause the trapping of air beneath the descending plunger and consequent distortion of the formed charge. Furthermore, the retraction of the plunger tends to develop suction above the charge, which also may produce distortion thereof. Our construction is particularly adapted to avoid these difficulties by providing means for permitting the escape of trapped air during compression of the charge, and for facilitating the influx of air beneath the rising plunger to prevent the development of sufficient suction to distort 25 the charge.

To accomplish this purpose, we provide apertures in spaced parts of the mold through which air can pass. These apertures are preferably provided by slightly spacing 30 the contiguous edges of the mold parts, a very slight opening along the joints between such parts being sufficient to permit air passage without allowing any substantial part of the material to escape. Any or all of the 35 joints between the parts of our mold and the plunger head may be spaced in this manner, the specific construction disclosed being especially suited for this purpose; for while such an arrangement necessarily increases the opportunity for charge material 40 to escape through the joints, the cut-away portions at the rear of the joints are adapted to accommodate such material, and the motion of the press tends to eject such overflow during normal operation.

Furthermore, the joint between table 19 and the mold walls 14 and 15, the joints between said walls, and the joint between said walls and plunger head 34, are so distributed 50 about the surface of the compressed charge that opportunity is offered for air entrapped adjacent any part of the charge to escape through a convenient joint. Furthermore, when the plunger head 34 is rising, air may 55 pass therebeneath not only through the joint between said head and the mold walls, but also through the vertical joints between adjacent mold wall sections, assuring a sufficient supply to prevent the development of an objectionable suction. It has been found 60 that, by suitable proportioning of the parts, the material collecting inside the joints will not interfere with the free passage of air therethrough. It will be apparent that the provision of an air passage for this purpose 65

greatly facilitates the rapid operation of the press, as the difficulty from the trapping of air and the development of suction beneath the plunger head is greatly increased as the speed of operation advances.

Any desired means for operating the plunger and mold may be employed. In the form disclosed a rock lever 39 pivoted on standard 30 is connected at one end to plunger 29, as by a slot and pivot connection, 70 the opposite end of the lever carrying a roller 40 engaging a cam slot in disk cam 41, which may be weighted to act as a fly wheel and which is mounted on shaft 42 rotating in a bearing in standard 43, which is carried by 80 the base of the machine. Block 10 carrying the mold is connected, as by link 44, to one end of a rock lever 45, pivoted on standard 30, the opposite end of the lever carrying a roller 46 engaging a cam slot in disk cam 85 47, which is also mounted on shaft 42.

Means is provided for rotating shaft 42, as by forming gear teeth 48 on the outer surface of disk cam 47, constituting said cam a drive pinion, connected to a source of power 49 by a suitable gear train which preferably includes a friction driving connection 50 to prevent breakage of parts of the press in the presence of a serious obstruction.

It will be apparent that the charges may be inserted in the press in any desired way, and while we have disclosed a specific feeding mechanism, we do not desire to be limited thereto; nor do we desire to be limited to 100 means for feeding separate lumps of material to the press, as the material may be fed in other forms.

In the preferred form of feed, we have disclosed an inclined chute 51 preferably 105 mounted on the frame of the machine as by a bracket 52, the chute terminating just above the mold so that lumps of material will roll down the chute and into the mold by gravity.

Means is provided for feeding the charge forming lumps one by one, preferably consisting of a gate, generally indicated at 53, normally adapted to prevent the passage of lumps from the chute into the mold. This 115 gate may be of any desired type, two forms being shown. In the construction disclosed in Figs. 1 to 7, the gate consists of a pair of oppositely disposed plates 54, pivoted adjacent their lower ends and having jaws 55 120 extending into the chute from opposite sides thereof through slots in the side walls. Jaws 55 are preferably shaped to prevent shearing into the lump when the gate is closed. Plates 54 are connected for simultaneous 125 operation, as by a pin and slot connection 56 between the plates below the pivots, so that the outward or inward motion of either jaw will be duplicated by the other jaw; and the jaws are normally held in closed 130

position in any desired way, as by a spring 57.

Means is preferably provided for automatically opening and closing the gate at the proper time. This may be of any desired form, but preferably consists of means, operated by the ejecting motion of the mold, to release a charge after the mold has completed its ejecting process and has 5 turned to closed position. One construction for accomplishing this result is disclosed, consisting of a trip plate 58 mounted on block 10 provided with a vertical check plate 59 and an outwardly bent trip arm 60, 10 so arranged that the forward movement of block 10 will bring check plate 59 across the lower end of chute 51, and simultaneously therewith trip arm 60 will contact with an extension 61 on outer plate 54, opening the 15 jaws and permitting a lump to pass therebetween into contact with check plate 59. Gate 53 is preferably spaced from the end of the chute by a distance approximately equal to the average diameter of the lumps, 20 and it will be apparent that with this construction gate 53 will be in the plane of contact between two lumps, and the return of the jaws 55 to normal position will not bring them into contact with a lump until the plate 25 59 has entirely receded from the end of the chute, permitting a charge to fall into the mold. This arrangement not only prevents any shearing or disfiguring of the lumps by 30 the gate, but also holds the lumps against 35 the gate by the force of gravity only.

It is also desirable to provide means for disengaging the formed charge or other adherent matter from the lower face of plunger head 38. Convenient means for this 40 purpose consists of a front plate 62, mounted on block 10 and preferably integral with the trip plate 58, the forward movement of the trip plate 58 carrying the front plate below the plunger and disengaging the 45 charge or adherent material therefrom in case the plunger does not serve to free it from the charge.

An alternative form of gate is disclosed in Fig. 8, consisting of a pair of side plates 50 54^a lying parallel to and against the walls of chute 51, pivoted thereto at one end and having their other ends formed into in-turned jaws 55^a projecting into the chute through slots in the opposite sides thereof, 55 the jaws being preferably formed similar to jaws 55. Plates 54^a have extensions connected beneath the chute by a pin and slot connection 56^a and are normally held in closed position by spring 57^a, the operation 60 being similar to that of the form of gate shown in Fig. 7. Extension 61^a is mounted on the outer jaw 55^a and is engaged by trip arm 60 in the manner above described.

It is desirable to have the floor and possibly the walls of the chute 51 slotted, as

at 63, (Fig. 8) to reduce the bearing surface and consequently the tendency of the lumps to adhere to the chute.

The operation of the machine is briefly as follows. 70

The charge forming lumps of material are placed in chute 51 and roll into position against gate 53. The machine is started, and block 10 is pushed forward by cam 47 and rock lever 45. Trip arm 60 opens the 75 gate, and the first charge rolls against check plate 59, the return of the mold to closed position, shown in Fig. 2, drawing the check plate away from the chute, and permitting the lump to fall into the mold, the remaining lumps settling against gate 53. Plunger 29 is now depressed by the action of cam 41 through rock lever 39, the plunger head 34 contacting with the lump and pressing it into shape, the trapped air escaping through the mold joints so as to permit rapid molding of the charge, any surplus material squeezing through the joints being accommodated in the cut-away portions. Plunger 29 then rises, the influx of air 80 through the mold joints preventing the development of suction; and, if the material used is adhesive, its engagement with the walls and bottom of the mold will permit the plunger head to break away from the charge. The mold is then forced forward, bottom plate 17 dropping away from the charge and breaking the connection therewith. Walls 15 preferably remain in closed 85 position until the mold is nearly clear of the frame, whereupon links 20 jerk the side walls sharply outward, breaking any engagement of the walls with the lump. This jerk, together with the arrest of the forward motion of the back mold wall 14, will project the charge forward out of engagement with the back wall and permit it to fall into a receiving means. During this ejecting motion, the succeeding charge has been dropped against check plate 59. The receding motion of the mold forces the side walls inward, either by action of links 20 or of the guide walls 12, or both; and bottom plate 17 is forced upwardly by engagement of lip 24 with the inclined surface 25 on the base, thus securely and firmly closing the mold, into which the succeeding charge drops as soon as the mold has reached its retracted position. 90

It will be apparent that there is no delay 95 in the operation of the press, a formed charge being replaced by another as soon as it is ejected, and being immediately pressed into shape. 100

It will also be evident that the parts are 105 easily and readily accessible for cleaning or replacement, the plunger being exposed by opening the split bearing 31. The mold, in the position shown in Fig. 3, is exposed 110 for complete cleaning without any detach- 115

ment of parts, and the portion of the framework surrounding links 20 is readily exposed by removing pins 23, a detachable connection of link 44 permitting the entire mold to be slid out of the machine. Consequently, any collection of dust, charge material or dressing therefor, in the moving parts of the machine can be readily and rapidly removed without leaving the machine idle for any length of time.

We have described a machine particularly adapted for use with soft, sticky material, and various details thereof which render it especially suitable for such use an example of such material is comminuted fruit such as figs combined with a laxative medicine and from which are formed laxative tablets or rolls. It will be apparent, however, that the general arrangement of parts is equally suitable for use with materials of other kinds.

While we have described a preferred form of our invention and certain modifications thereof, it will be apparent that numerous other changes may be made within the spirit of our invention as set forth in this specification.

We claim:

1. In a press, a sectional mold, including a central mold wall section and lateral mold wall sections, means for compressing a charge while the parts are in molding position, means for retaining said sections in closed position to form a mold cavity, means for shifting the central section, and means for simultaneously swinging the side sections outwardly to free the charge from the mold.

2. In a press, a carrying element, means for reciprocating said element between molding and ejecting positions, a central mold section mounted on said element, side sections carried by said element, means for compressing a charge while the parts are in molding position, means for shifting said side sections away from the center section when the carrier element is shifted toward ejecting position, and means for returning said side sections to closed position during the return of the mold to molding position.

3. In a press, a reciprocating mold having movable sections, means for compressing a charge while the parts are in molding position, guides for maintaining the mold in closed position during molding of the charge, means for shifting movable sections of the mold out of engagement with said guides, and means for opening and closing said mold while out of engagement with the guides to free the charge from the mold.

4. In a press, a reciprocating sectional mold, including a central section transverse to the line of reciprocation, and lateral sections movable outwardly from the central section, and link means connected to said

lateral sections adapted to move said sections outwardly during the movement of the mold from molding to discharging position and to shift said sections inwardly to closed position during the return of the mold.

5. In a press, a reciprocating mold, a swinging end therefor, means for retaining the end in closed position to form a mold wall during molding, and means for simultaneously shifting said mold laterally and swinging the end away from the mold to free the charge from the mold.

6. In a press, a sectional mold including side wall sections and an end section forming a mold cavity, and means for swinging a plurality of the side wall sections and the end section away from the mold cavity to free a charge from engagement with the mold.

7. In a press, a reciprocating sectional mold including a plurality of side sections and an end section, means for retaining said sections in closed relation to form a cavity in molding position, means for shifting the mold from molding to discharging position, and means for shifting said sections away from the mold cavity prior to the return of the mold to molding position, so as to free a charge from the mold.

8. In a press, a mold including a side wall portion, a swinging end, means for reciprocating said mold between the molding and discharging positions, a fixed support for said swinging end adapted to retain it in engagement with the side wall portion in molding position, and to release said end when the mold is reciprocated prior to its return to molding position so as to permit the end to swing outward by gravity and permit discharge of the charge.

9. In a press, a sectional mold including a reciprocating carrier and a plurality of sections hinged thereto, a guide member for each of said sections adapted to retain them in closed relation during molding, means for shifting said carrier and the mold sections carried thereby to free said sections from the guide members, and means for thereafter moving each of said sections outwardly to free the charge from the mold.

10. In a press, a sectional mold including a plurality of swinging sections adapted to form a mold cavity when in closed position, fixed supports engaging each of said sections to maintain it in closed position during the compressing of the charge, means for shifting the mold to free a plurality of sections from said fixed supports, and means for thereafter swinging said sections outwardly to free the charge from the mold.

11. In a press, a sectional mold including a reciprocating carrier, a section of the mold mounted in fixed position on said carrier, lateral mold sections hingedly connected to the carrier, an end mold section

- hingedly connected to the carrier, means for retaining the sections in closed relation, means for shifting the mold sections out of engagement with the retaining means so as to permit the end section to drop away from the mold by gravity, and means for swinging the lateral sections outwardly to free the charge from the mold. 5 to permit the bottom to swing into open position and free the charge therefrom. 65
12. In a press, a reciprocating mold adapted to be shifted from molding to discharging position, and means for feeding successive charges to the mold including means connected to the mold operated by the shift thereof into molding position to actuate said feeding means so as to feed a charge to the mold. 10 70
13. In a press, a mold, means for reciprocating said mold between molding and discharging positions, means for feeding successive charges to the mold, including means, actuated during the shift of the mold to discharging position, to feed a single charge into position adjacent the mold, and means, operated by the return of the mold to molding position, to feed said charge into the mold. 15 75
14. In a press, a reciprocating mold, a feed chute for feeding successive separate individual charges of plastic material to the mold, a gate in said chute, and means, connected to the mold and operative during the reciprocation thereof, to open the gate and feed a charge to the mold. 20 80
15. In a press, a mold, means for reciprocating the mold between molding and discharging positions, a feed chute having an end adjacent the mold, a gate in said chute, means connected to the mold and operative during the forward motion of the mold 25 85
- toward discharging position, to open the gate and close the end of the chute, feeding a charge past the gate, and also operative during return of the mold to close the gate and open the end of the chute to permit said charge to enter the mold. 90
16. In a press, a sectional mold having a permanently open end, a reciprocating plunger adapted to enter said end and compress a charge, means for shifting said mold laterally to discharging position, and means 95
- for swinging the sections of the mold outwardly to free the charge from the mold prior to its return to charge-compressing position. 100
17. In a press, a sectional mold having a permanently open end, a reciprocating plunger adapted to enter said end and compress a charge, a swinging bottom section adapted to close the opposite end of the mold, a fixed support for maintaining the bottom section in closed position during compression of the charge, and means for thereafter shifting said mold and bottom laterally out of engagement with the fixed support 105 110
- to permit the bottom to swing into open position and free the charge therefrom. 115
18. In a press, a mold having a permanently open end, means for feeding a charge of material into the mold through said open end, a reciprocating plunger adapted to enter said end and compress a charge in the mold, means for shifting the mold laterally to eject the compressed charge from the mold, and means for simultaneously freeing the end of the plunger from adherent material. 120
19. In a press, a mold having a permanently open end, a reciprocating plunger adapted to enter said end and compress a charge in the mold, means for shifting the mold laterally to eject the compressed charge, and means mounted on said mold and operated by the shift of the mold to free said plunger from adherent material. 125
20. In a press, a mold including a plurality of movable sections forming a central cavity, the portions of said sections outside of and immediately adjacent the joints between sections being cut away to provide pockets for the reception of material forced through said joints. 130
21. In a press, a mold including a plurality of relatively movable sections having abutting inner faces composing continuous side walls of the mold, said sections being cut away along their abutting faces immediately adjacent the said side walls to provide pockets for the reception of material forced between said edges, and an end section coinciding exactly with the edges of the side walls at one end and spaced from said walls except at said edges, providing a space adjacent the mold cavity formed by the side walls and end into which material squeezed through the junction between the side walls and end may be received. 135 140
22. In a press, a mold having a molding cavity with a tubular opening, a plunger closely fitting said opening and adapted to slide inwardly therein to mold a charge in said cavity, said mold being provided with apertures to permit the escape of air from the cavity during the inward movement of the plunger. 145
23. In a press, a mold having a molding cavity with a tubular opening, a plunger closely fitting said opening and adapted to slide inwardly therein to mold a charge in said cavity and outwardly to release the charge, said mold being provided with apertures to permit the ingress of air beneath the plunger during its outward movement to prevent the formation of a charge-deforming vacuum. 150
24. In a press, a mold comprised of a plurality of relatively movable sections forming a molding cavity with a tubular opening, a plunger closely fitting said opening and

adapted to slide inwardly therein to mold a charge in the cavity, said mold being provided with apertures at the joints between the relatively movable sections to permit the escape of air from the cavity during the inward movement of the plunger.

25. In a press, a mold comprised of a plurality of relatively movable sections forming a molding cavity with a tubular opening, a plunger closely fitting said opening adapted to slide inwardly therein to mold a charge in the cavity, and outwardly to release the charge, said mold being provided with apertures at the joints of the sections to permit the ingress of air beneath the plunger during its outward movement, to prevent the formation of a charge-deforming vacuum.

26. In a press, a mold having a tubular molding cavity closed at one end, a plunger closely fitting said cavity and adapted to slide inwardly therein from the other end to mold a charge, said mold being provided with a plurality of longitudinal apertures in the walls of the cavity adapted to permit the escape of air therefrom during the inward movement of the plunger.

27. In a press, a mold having a tubular molding cavity, a wall closing one end of said cavity, a plunger closely fitting the cavity and adapted to slide inwardly from one end thereof to compress a charge, and a wall at the opposite end closing said cavity, apertures being provided between said cavity and end wall to permit the escape of air from the cavity during the inward movement of the plunger.

28. In a press, a mold comprised of a plurality of relatively movable sections adapted to form a molding cavity, and means for compressing a charge in said cavity, the abutting edges of said members being sufficiently spaced to permit the air to pass readily therebetween, and said mold being provided with recesses communicating with the space between said abutting edges and with the outer air, to permit the ready flow of air between the edges.

Signed at New York city in the county of New York and State of New York this 20 day of February A. D. 1920.
